CLAIM

The ornamental design for a firearm suppressor core, as shown and described.

DESCRIPTION

FIG. 1 is a top, front, right side perspective view of a firearm suppressor core in accordance with our new design;

FIG. 2 is a top, rear, left side perspective view of the firearm suppressor core of FIG. 1;

FIG. 3 is a top view of the firearm suppressor core of FIG. 1;

FIG. 4 is a bottom view of the firearm suppressor core of FIG. 1;

FIG. 5 is a front view of the firearm suppressor core of FIG. 1;

FIG. 6 is a rear view of the firearm suppressor core of FIG. 1;

FIG. 7 is a left side perspective view of the firearm suppressor core of FIG. 1;

FIG. 8 is a right side view of the firearm suppressor core of FIG. 1;

FIG. 9 is a top, front, left side view of the firearm suppressor core of FIG. 1;

FIG. 10 is a bottom, rear, right side perspective view of the firearm suppressor core of FIG. 1;

FIG. 11 is a top, rear, right side perspective view of the firearm suppressor core of FIG. 1;

FIG. 12 is a front, left side perspective view of the firearm suppressor core of FIG. 1;

FIG. 13 is a cross-sectional view of the firearm suppressor core of FIG. 1, along line 13-13;

FIG. 14 is a cross-sectional view of the firearm suppressor core of FIG. 1, along line 14-14;

FIG. 15 is a cross-sectional view of the firearm suppressor core of FIG. 7, along line 15-15;

FIG. 16 is a cross-sectional view of the firearm suppressor core of FIG. 7, along line 16-16; and,

FIG. 17 is a cross-sectional view of the firearm suppressor core of FIG. 7, along line 17-17.

The broken lines immediately adjacent the shaded areas represent the bounds of the claimed design. All broken lines are directed to environment and are for illustrative purposes only and form no part of the claimed design.
